(57) **CLAIM**

The ornamental design for a handle for faucet, as shown and described.

DESCRIPTION

FIG. 1 is a perspective view of front, top and right side of a handle for faucet according to our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The handle for faucet is used for switching a shower and a faucet or adjusting water flow.

The portions of the article in broken lines are shown for illustrative purposes only and form no part of the claimed design.
